UNITED STATES PATENT OFFICE.

ARNOLD TURNER, OF DANBURY, CONNECTICUT.

HAT-SIZING MACHINE.

1,118,079.

Specification of Letters Patent. Patented Nov. 24, 1914.

Application filed September 20, 1911. Serial No. 650,449.

To all whom it may concern:

Be it known that I, ARNOLD TURNER, a subject of the King of England, and resident of Danbury, in the county of Fairfield and State of Connecticut, have invented certain new and useful Improvements in Hat-Sizing Machines, of which the following is a specification.

This invention relates to hat forming machinery and refers to that class of machines employed for sizing, shrinking and felting hat bodies, and is more particularly termed an "apron settling machine."

Heretofore it has been the practice in the manufacture of fur hats to work the newly formed and delicate hat bodies when they first come from the former, down to a smaller size, by hand, preparatory to being further felted, shrunk and sized in various forms of machines. This hand working has thus been accomplished by first dipping four or five hats in very hot water, then rolling them into a bundle and covering the bundle with burlap, and while in this condition they have been rolled backward and forward upon a bench or table for the purpose of working the fur together and making a thicker but shorter body.

It has therefore been my object to produce a practical machine for doing the above work of operating upon newly formed hat bodies preparatory to being further felted, shrunk and sized in a different form of machine; to design a machine which could be operated by power and attended by a single operator, and whereby a number of hat bodies may be operated upon simultaneously; to provide adjusting means whereby hat bodies of different sizes, or bundles of hat bodies comprising a larger or smaller number may be properly treated as occasion may require, and finally to provide a machine for the above purpose whereby the work referred to may be speedily and effectively accomplished and very much cheaper than the hand work heretofore employed.

With these and other objects in view the invention consists in the construction and novel combination and arrangement of parts hereinafter fully described, illustrated in the accompanying drawings, and pointed out in the claims hereto appended, it being understood that various changes in the form, proportion, size and minor details of construction within the scope of the claims may

be resorted to without departure from the spirit of sacrificing any of the advantages of the invention.

Similar characters of reference denote like or corresponding parts throughout the several figures of the accompanying drawings forming a part of this specification, and upon which—

Figure 1 shows a plan view of my improved apron settling machine complete; Fig. 2 is a side view of the same; Fig. 3 is an end view as seen from the right of Figs. 1 and 2; and Fig. 4 is a central vertical longitudinal section taken on line 4—4 of Fig. 1.

In the designing of this machine I have endeavored to provide a construction which would produce an operative movement upon the hat bodies as near like the hand work heretofore employed as is possible, and which consisted principally of a backward and forward rolling motion, of the bundle of hat bodies when folded and rolled within a cloth and forming an elongated roll-shaped bundle. My improved machine therefore includes a movable endless apron having both a forward and backward movement for rolling the bundles of hats backward and forward upon a bed, and whereby the said hat bodies are gradually passed through and out of the machine. The hats are then again dipped in hot water, refolded and rolled in the cloth, preparatory to being again passed through the machine in a similar manner.

Referring in detail to the characters of reference marked upon the drawings, 5 represents the frame of the machine which as will be noted consists of two side uprights, 5^a and several intermediate connected cross pieces for tying together and supporting the said side uprights.

6 represents the main driving shaft upon which is mounted belt pulleys 7 for operating the same. This driving shaft is suitably journaled in bearings formed in the said uprights, and upon this shaft is mounted a gear 8, a beveled gear 9, an eccentric 10, and a clutch sleeve 11. A drum 12 is loosely mounted upon the said shaft and serves to support and guide one end of an endless flexible apron 13, which is preferably formed of rubber and provided with a series of transverse corrugations upon its face better to engage and manipulate a bundle

110

of hat bodies. The upper and forward end of the endless apron is in a like manner passed over and supported upon a second drum 14 which is fixed to a driving shaft 15. 5 also journaled in bearings of the said uprights and operated through worm gear eccentric and clutch mechanism again to be referred to, from the main shaft 6 before mentioned. This drum 14 therefore serves 10 as the driver, while the drum 12 is but an idler, the apron being carried over the latter by the action of the former, and similar to that of an ordinary belt; connecting a driven and a driving pulley. A series of 15 transverse rolls 16; see Fig. 4; are journaled against the inside of the uprights and between the before mentioned rolls in a way to support the lower portion of the apron when acting upon a bundle of hats. This 20 insures a uniform pressure upon the hats while being rolled backward and forward and up the incline floor or bed 17 which is arranged between the uprights and parallel to the under face of the said flexible apron 25 so as to form a uniform space between the two throughout the operative movement of the said apron.

The bed referred to is composed of a series 30 of boards that extend across the underside of the machine and are supported upon long curved metal rails 18 in a way to form one integral part; that is, supported at the corners of the machine and adapted to be raised and lowered for a purpose later to be described. The end portions 19 of the rails for this bed are connected to and supported upon the adjustable top cross-pieces 20 located at the opposite ends of the machine and guided upon vertical guides 21 carried 35 by brackets 22 secured to the side uprights. A second cross-piece 23 is also mounted upon these guides, and the adjusting screws 24 and a spring 25 serve to yieldably support the upper cross-piece upon the lower one, 40 said springs being seated between the upper cross-piece, and a lower collar upon the screw, while the screw freely passes through the said top cross-piece and threadably engages the lower cross-piece.

45 The bed, nuts and top cross-pieces are thus closely supported on the threaded rods and guide and are further yieldably supported upon the lower cross-piece 23 through the medium of a yieldable spring 25 mounted 50 upon the before mentioned adjusting screws 24. This serves to permit both of the said cross-pieces 20 and 23 mounted upon the rod to be raised and lowered as occasion may require in the vertical adjustment of the bed.

55 with relation to the apron 13: The two pairs of these cross-pieces at each end of the machine are connected and supported by the uprights 5^a through the medium of the screws 24 and guides 21 as before described.

60 The lower cross-pieces 23 are directly sup-

ported upon the four cams 26 located immediately beneath the ends of the said cross-pieces at the several corners of the machine, the said cams being mounted upon cross-shafts 27 and 28 journaled in bearings of the 70 uprights. The latter shaft 28 is provided with a hand wheel 29 whereby it and the four cams may be simultaneously adjusted through the medium of suitable connecting rods 30 extending along the opposite sides 75 of the machine and thus connecting the pairs of side cams and the shafts in a way to insure the simultaneous adjustment of all four cams, and thus the raising or lowering of all four corners of the bed before mentioned. 80 This adjustment is to accommodate bundles of different thicknesses by bringing the bed toward or from the under face of the flexible apron, and which rolls the bundles of hat bodies 31 backward and forward; and 85 finally out from the rear end of the machine.

The means employed for obtaining this forward and backward movement of the apron is best illustrated in Figs. 1 and 2 90 wherein it will be noted that there are two movements imparted to the feed drum, one through the bevel gear connections 9 to 32, and the other through the eccentric 10 which imparts a reciprocating movement to the 95 worm 33 splined to the intermediate shaft 34 journaled in bearings 35 and further rotated through the medium of the before mentioned beveled gear connections. This reciprocatory rotary worm meshes with and 100 drives a worm gear 36 mounted upon the drum shaft 15 in the manner and for the purpose before described. The clutch sleeve 11 which is splined to the main shaft 6 serves to engage with the clutch face on the 105 side of the eccentric so that the apron operating mechanism connected with the eccentric may be started or stopped at will, the said clutch being operated by lever 37 pivotally connected to a bracket 38 secured to 110 one of the side uprights 5^a. The beveled gear 9 is splined to the main shaft 6 and thus always turns with it. The eccentric is bored to receive the hub of said gear 9 and is free to run with it or not according to the position of clutch 11. This permits of either a continuous rotary or a reciprocatory motion of the apron, the former being desired at the start, as being more gentle.

The conveyer or transporting mechanism 120 39 is supported by two forward brackets 40 and two rearward brackets 41, all of which are properly secured to the top of the side uprights. Cross shafts 42, 43 and 44 are journaled in these uprights while the shaft 125 45 is journaled in an adjustable bearing 52 carried by the bracket 40 and all said shafts are provided with sprockets to engage the open links of the chain 46 of the conveyer and to which the cross strips 47 are con- 130

nected. A further sprocket 48 is attached to one end of the cross shaft 45 and connected by the sprocket chain 49 with a lower sprocket 50 mounted upon a short shaft 5 journalized in a stud 51 and bearing a gear 53 that meshes with and is driven by the before mentioned gear 8 upon the main shaft 6. This conveyer, like the apron, is an endless form of device, the intermediate part of 10 the top side being supported upon the sprockets carried on the intermediate shaft 44, while the returning underside of the conveyer is similarly supported upon sprockets carried on the shaft 43. The front shaft 45 arranged across the front of the machine is 15 adapted to be shifted slightly backward or forward by means of the adjusting device 52, whereby the wear and slack of the conveyer can be taken up from time to time as 20 occasion may require.

As before stated the apron 13 is alternately given a forward and backward movement when the clutch is in engagement, and in addition to this I have provided means to 25 insure a slightly greater forward movement than backward movement, or, in other words, the bundles of hats are alternately given a full rotation in a forward direction, and then a reverse roll of about half that 30 amount. This obviously results in a continual forward and backward roll of the bundle of hats and a final delivery of the same from beneath the apron at the rear, where the operator is in attendance to 35 receive and unroll the hat bodies. The four or five hat bodies are then separately crozed, rolled and wrapped into a bundle again as before and laid upon the conveyer, which carries it forward and drops it into the front 40 end of the machine for a further and similar operation, said roll being kept in proper position and guided to the apron by means of the shield 53 supported on brackets 54 secured to the before mentioned uprights 5^a. 45 The forward movement of the apron is the sum of the motion imparted to the worm gear by the rotary motion of the worm, through the bevel gears, plus the forward impulse the whole worm gives to the worm 50 gear by virtue of the eccentric. The backward movement of the apron is the excess of the backward impulse the whole worm gives to the worm gear by virtue of the eccentric, over the motion in the opposite direction im- 55 parted to the worm gear by the rotary motion of the worm through the bevel gears, since this latter movement is always in the same direction and amounts to less than the eccentric motion.

60 Having thus described my invention, what

I claim and desire to secure by Letters Patent is:

1. In a machine of the class described, the combination of a bed upon which bundles of hat bodies may be placed, an endless apron 65 over the bed, means for imparting thereto an alternate forward and backward movement in a way to insure a forward and backward roll to a bundle of hats when placed between the said apron and bed, upper and 70 lower bed-supporting bars at opposite ends of the machine, means for adjusting the distance between said bars, and a series of connected cams for simultaneously raising and lowering said lever bar to adjust the bed 75 toward and from the apron.

2. In a machine of the class described, the combination with suitable drums, of an apron mounted thereon, means for imparting thereto a backward and forward motion, 80 a bed arranged below the apron, upper and lower bed-supporting bars at opposite ends of the machine, means for adjusting the distance between said bars and yieldingly support the upper bar, and means for adjusting 85 the lower bars to raise or lower the bed toward or from the apron.

3. In a machine of the class described, the combination with suitable drums, of an apron mounted thereon, means for imparting thereto a backward and forward motion, 90 a bed arranged below the apron, cross-pieces upon which the bed is mounted, a lower pair of cross-pieces for supporting the first mentioned cross-pieces, springs between the said 95 first and second mentioned cross-pieces, and means for simultaneously adjusting both of said lower cross-pieces and the bed with relation to the apron.

4. In a machine of the class described, the 100 combination with suitable drums, of an apron mounted thereon, means for imparting thereto a backward and forward motion, a bed arranged below the apron, and comprising a series of transverse slats and longitudinal supporting rods, parallel transverse bars at opposite ends of the machine adjustable toward and from each other, supporting the ends of said rods, a series of cams for raising and lowering said transverse bars, 105 and means for simultaneously operating said cams to effect said adjustment.

Signed at Danbury in the county of Fairfield and State of Connecticut this 16 day of September A. D., 1911.

ARNOLD TURNER.
